UNITED STATES PATENT OFFICE.

WILLIAM A. SMITH, OF NEW YORK, N. Y.

INCANDESCENT OIL-BURNER.

SPECIFICATION forming part of Letters Patent No. 594,439, dated November 30, 1897.

Application filed January 15, 1897. Serial No. 619,308. (No model.)

To all whom it may concern:

Be it known that I, WILLIAM A. SMITH, of New York city, in the county and State of New York, have invented new and useful Improvements in Incandescent Oil-Burners, of which the following is a full, clear, and exact description.

My invention relates to improvements in central-draft burners of that kind in which the air for the central tube is received through an opening in the side of the burner; and it consists of certain improvements in construction whereby an increased amount of air may be furnished both for the inner and outer draft.

Reference is to be had to the accompanying drawings, forming a part of this specification, in which similar characters of reference indicate corresponding parts in all the figures.

20 Figure 1 is a central vertical section through the burner and chimney. Fig. 2 is a section of the upper end of the burner, illustrating the manner of using a central support for the mantle. Fig. 3 is a horizontal section upon the line 3 3 of Fig. 1, and Fig. 4 is an end view of the upper end of the wick-raising slide.

25 The lower end of the burner is provided with a burner-base A, which is threaded at its lower end, as shown at a, for screwing into the lamp-fount. It is also provided with similar threads a' upon its upper end, upon which is screwed the upper portion of the burner-casing D. This burner-casing has attached

30 thereto and extending centrally upward therefrom the inner tube B, which forms the center-draft passage for the burner and the inner wall of the annular wick-chamber. The lower end of this tube B is connected by

35 a side-extending passage P with the outer air. The walls p thereof meet at the top of this passage at an angle. The burner-casing D is formed with threads adapted to screw upon the threaded upper portion a' of the burner-base. The burner-casing is provided

40 with slots d or any other suitable openings, which admit the air into the interior of the casing. The casing surrounds the opening of the side-draft passage P, and the air for the inner tube passes through the perforations d in the casing D and then through the side-draft passage P to the inner tube B.

The upper portion of the inner tube B is surrounded by an outer tube C, the space between these two tubes being just sufficient to nicely receive the wick. The tube C, a short distance above the upper portion of the side-draft passage P, is enlarged, as shown at C'. It is also provided with horizontal and vertical flanges, as shown at C² C³, the flange C² slipping over an upward vertical extension A' upon the burner-casing A. This extension A' is circular in outline and extends a short distance above the top of the side-draft passage P. The outer casing C may be readily removed from about the wick, leaving the entire upper end of the wick exposed, so that the wick may be readily applied about the inner tube and adjusted in position.

45 The adjustment of the wick is secured by means of a slide H, which at its upper end entirely surrounds the inner tube B and is provided with notches or projecting spurs, as shown at h in Fig. 4, which spurs are adapted to engage the wick and hold the same securely. At each end this slide is cut away upon one side, so as not to interfere with the side-draft passage P. The lower end of this slide is connected to a rack-bar I, which extends upward through the center of the inner tube B. To accommodate this, a tube F, just large enough to contain the rack-bar, is attached centrally to the lower end B' of the tube B. This tube F is open at its lower end to receive the rack-bar.

50 Extending to one side from the tube F is a tube L, which contains and supports a shaft K, carrying at its inner end a pinion J, meshing with the rack-bar I, and at its outer end a hand-wheel L', by which the shaft is operated. The burner-casing D, which screws upon the upper end of the burner-base, has an inwardly-projecting flange D', which presses upon the horizontal flange C³ upon the lower end of the tube C and holds the same securely down upon the end of the cylinder A'. The upper end of the casing D above the flange D' flares outwardly and is provided with a ring D², which is adapted to receive the removable cap carrying the chimney and mantle.

55 The cap E is provided with a ring adapted to slide within the ring D² upon the casing D. The ring on the cap D has a concave recess adapted to receive the points of the adjust-

ing-screws R, which may be adjusted to hold the cap in place. The cap slopes inward to the base of the chimney and is provided with a ring E², surrounding the base of the chimney, 5 and fingers E³, extending upward therefrom and adapted to securely hold the chimney.

The casing D and the cap E are provided with perforations d' and e, admitting air to the interior thereof and around the outer tube 10 C. The upper portion of the cap E is formed as a cone E', which is provided with a circular hole in its upper surface large enough to just pass over the wick W. Just about the 15 edge of this hole the cap is flared inwardly, so as to direct the air-draft upon the base of the flame.

To the base of the cone E' is fixed a small block e', which is threaded to receive a small set-screw n. To the same block is attached 20 a short tube N', which receives the lower end of a post or wire N, extending upward within the chimney and supporting the mantle O. The latter at its base closely surrounds the top of the cone E.

25 The upper portion of the small tube F, which receives the rack-bar I, is supported from the inner tube B by means of narrow fins f. These do not furnish any material interruption to the passage of the air and firmly support the 30 tube. In the upper end of this tube is placed a bar M, which carries the inner air-spreader M'. This latter is formed as a small disk having its under surface beveled, so as to deflect the air outwardly, and is placed at such 35 a height that its upper surface is approximately on a level with the upper surface of the cone and cap E', and both so that they will deflect the air upon the base of the flame.

40 To further concentrate the draft and deflect it into proper relation with the flame, a ring B² is placed upon the inner surface of the tube B, which ring first deflects the air inward against the conical under surface of the spreader M'.

45 In Fig. 2 the upper end of the spreader M' is provided with a hole adapted to receive the lower end of a rod N², which supports the mantle O. In this way the mantle is given a central support if at any time desired. The 50 outer support, as shown in Fig. 1, is, however, deemed preferable. The mantle O may be made of any material thought suitable for that purpose. The mantles now in use for incandescent gas-lamps are found satisfactory.

55 In Fig. 3 the position of the wick while passing the side-draft passage and support for the inner tube is shown. That portion of the wick above the side-draft passage E will have the edges of the wick brought in contact. 60 If desired, these edges may be stitched together above this point. This construction makes it possible to use an ordinary flat wick, and yet to obtain a circular blaze with a center draft. It also makes it possible to 65 apply a center-draft burner to any ordinary lamp-fount without the necessity of extending the center-draft tube through the bottom of

the fount, as is customary with such lamps. This burner may thus be made to take the place of ordinary lamp-burners. As the passage for the wick is enlarged just above the inside connection and air-passage P, the wick has an opportunity to spread so as to pass the same. The manner of connecting the upper portion of the burner-base or the casing D 70 upon the lower portion A makes it possible to remove the upper portion of the burner and the outer tube C, so that the wick is very accessible without removing the burner from the lamp. This makes it very easy to place 75 a new wick upon the lamp or to readjust the old wick. The wick may be held in place by the fingers upon the inner tube, while the outer tube C is slipped over the same. This will make the placing of a new wick in the 80 lamp and the readjusting of the old wick much easier than with the ordinary circular burner.

To the base of the cone E' is fixed a small block e', which is threaded to receive a small set-screw n. To the same block is attached 20 a short tube N', which receives the lower end of a post or wire N, extending upward within the chimney and supporting the mantle O. The latter at its base closely surrounds the top of the cone E.

90 In lighting the lamp the cap E is removed, carrying with it the chimney and the mantle. The wick is turned up so that its upper end is a very little above the end of the tubes B and C and is then lighted. The cap is then placed in position and the lamp permitted to burn for a short interval as so adjusted. After 95 a short interval the wick is turned up until it reaches the position shown in the drawings, or slightly below the air-spreader M' and the top of the cap E'. At or about this point the blaze will become blue in color and one of great heat, which will transform the mantle into an incandescent one, which gives a clear steady light. This blue flame is caused by the oil being transformed into a gas at the upper end of the wick, which gas is thoroughly 100 mixed with air by reason of the action of the inner and outer spreaders or deflectors. This makes it possible to obtain a clear incandescent light similar to that given by a gas flame and an incandescent mantle, and by the use 105 only of ordinary illuminating-oil. This extends the field for incandescent lighting much beyond that possible where gas must be used. The chimney G is an ordinary glass chimney, such as commonly used for incandescent burners.

Having thus described my invention, I claim as new and desire to secure by Letters Patent—

1. In a lamp-burner, the combination of a 110 hollow circular section screw-threaded upon the upper and lower ends and adapted to screw into the lamp-fount, having also a hollow cylinder of slightly-reduced diameter extending 115 upward above the upper screw-threads and interrupted at one side by an inwardly-extending air-passage, and a central cylinder attached thereto and similarly interrupted on one side forming the inner wall of the wick-chamber, with a tube forming the outer wall 120 of the wick-chamber and flaring at its lower end to fit over the upwardly-extending cylinder upon the lower threaded section, and an outer base-section consisting of a cylindrical 125

section of larger diameter than said cylinder upon the lower threaded section and screwing upon the upper threads thereof, said cylinder having draft-openings therein, and an inwardly-projecting flange at the upper end of this cylinder engaging the upper surface of the flaring base of the tube forming the outer wall of the wick-chamber, substantially as described.

2. In a lamp-burner, the combination of a hollow circular section screw-threaded upon the upper and lower ends and adapted to screw into the lamp-fount, having also a hollow cylinder of slightly-reduced diameter extending upward above the upper screw-threads and interrupted at one side by an inwardly-extending air-passage, and a central cylinder attached thereto and similarly interrupted on one side forming the inner wall of the wick-chamber, with a tube forming the outer wall of the wick-chamber and flaring at its lower end to fit over the upwardly-extending cylinder upon the lower thread-section, an outer base-section consisting of a cylindrical section of larger diameter than said cylinder upon the lower threaded section and screwing upon the upper threads thereof, said cylinder having draft-openings therein, an inwardly-projecting flange at the upper end of this cylinder engaging the upper surface of the flaring base of the tube forming the outer wall of the wick-chamber, an outwardly-projecting flange attached to the same part having draft-openings, and a chimney-supporting base carried on said last flange and provided with draft-openings, substantially as described.

3. In a lamp-burner, the combination of a hollow circular section screw-threaded upon the upper and lower ends and adapted to screw into the lamp-fount, having also a hollow cylinder of slightly-reduced diameter extending upward above the upper screw-threads and interrupted at one side by an inwardly-extending air-passage, and a central cylinder attached thereto and similarly interrupted on one side forming the inner wall of the wick-chamber, with a tube forming the outer wall of the wick-chamber and flaring at its lower end to fit over the upwardly-extending cylinder upon the lower threaded section, an outer base-section consisting of a cylindrical section of larger diameter than said cylinder upon the lower threaded section and screwing upon the upper threads thereof, said cylinder having draft-openings therein, an inwardly-projecting flange at the upper end of this cylinder engaging the upper surface of the flaring base of the tube forming the outer wall of the wick-chamber, an outwardly-projecting flange attached to the same part having draft-openings, and a chimney-supporting base carried on said last flange and provided with draft-openings, and having a hollow frustum of a cone embracing the upper end of the wick-chamber and bent inward at its upper end to deflect the air upon the flame, substantially as described.
